United States Patent Office.

HARRISON PARKMAN, OF PHILADELPHIA, PENNSYLVANIA.

Design No. 4,969, dated May 30, 1871.

DESIGN FOR A SPADE.

The Schedule referred to in these Letters Patent and making part of the same.

To all whom it may concern:

Be it known that I, HARRISON PARKMAN, of Philadelphia, in the county of Philadelphia and State of Pennsylvania, have invented and produced a new and original Design for a Spade; and I do hereby declare the following to be a full, clear, and exact description of the same, reference being had to the accompanying drawings making a part of this specification, in which the figure is a front elevation.

This invention consists of a spade having sides that are inclined outward from the upper corners, each to the same extent, and having a rounded point.

Referring to the drawing—

a is the spade;
b, the inclined sides thereof; and
c, the rounded point.

I am aware that a round-pointed spade is no new thing of itself, but I have yet to learn of a spade that has a rounded point in combination with sides that are inclined outward from the upper corners.

I claim as my invention—

The design for a spade herein shown and described.

HARRISON PARKMAN.
